AUTOMATIC HAT BLOCK CHUCK

Frederick R. Marindin, Newtown, Conn., assignor
to Doran Brothers, Incorporated, Danbury,
Conn.

Application April 3, 1950, Serial No. 153,635

17 Claims. (Cl. 223—20)

1

This invention relates to apparatus for attaching hat block to a hat processing machinery. One of the objects of this invention is to provide such block attaching apparatus which will greatly increase the efficiency of the operators of hat making machinery. Another object is to provide apparatus of the above character for use on hat making machinery which will be simple, practical, and thoroughly durable. Another object is to provide a new and improved hat block chuck. Another object is to provide a hat block chuck of the above character which is so constructed that it will be well able to withstand continuous hard usage. Another object is to provide apparatus of the above character whose manufacture will be economical both from the standpoint of labor and materials used. Another object is to provide apparatus in which the structural elements are so disposed as to attain a high degree of strength without heavy construction. A further object is to provide apparatus of the above character which will permit a maximum number of hat bodies to be operated upon in a minimum amount of time. A still further object is to provide apparatus of the above character which is automatically operated by the control mechanism of the machine on which it is mounted. Other objects will be in part obvious and in part pointed out hereinafter.

The invention accordingly consists in the features of construction, combinations of elements, and arrangements of parts as will be exemplified in the structure to be hereinafter described and the scope of the application which will be indicated in the following claims.

In the accompanying drawing in which is shown one of the various possible embodiments of this invention,

Figure 1 is a side elevation of a machine having the automatic hat block chuck installed thereon:

Figure 2 is a view on an enlarged scale of a portion of Figure 1, the chuck and a portion of the machine being vertically sectioned, the control levers and chuck being in inoperative positions;

Figure 3 is a view substantially similar to Figure 2 with the parts in operative positions;

Figure 4 is a vertical section taken along the line 4—4 of Figure 3.

Figure 5 is a front elevation on an enlarged scale of the portion of the machine shown in Figure 1;

Figure 6 is a vertical section on an enlarged scale taken on the line 6—6 of Figure 2;

2

Figure 7 is a staggered vertical section on an enlarged scale taken on the line 7—7 of Figure 2;

Figure 8 is a horizontal, staggered section on an enlarged scale taken on the line 8—8 of Figure 2;

Figure 9 is a vertical section on an enlarged scale taken on the lines 9—9 of Figure 5 showing certain portions of the control mechanism of the machine and chuck;

10 Figure 10 is an exploded perspective view on an enlarged scale of portions of the control levers and mechanism associated therewith shown in Figure 1; and

Figure 11 is a diagrammatic perspective view 15 of the control levers for the chuck and machine and certain parts of the operating mechanism of the automatic chuck.

Similar reference characters refer to similar parts throughout the several views of the drawings.

As conducive to a clearer understanding of certain features of this invention, it might here be pointed out that in operating hat making machinery on which hat bodies are mounted, on hat blocks, the blocks must be connected to and disconnected from each machine at the beginning and ending of each operation. Heretofore, the mechanism of the chuck which mounts a hat block on a machine has been operated by control

25 mechanism which is separate and distinct from the control mechanism which operates the machine. Thus, in placing the machine in operation, a hat block heretofore first had to be mounted on the machine by operating the hat block chuck control mechanism and then other mechanism had to be operated to place the machine in operation. At the end of an operation,

30 the machine automatically stopped but the hat block chuck control mechanism had to be again operated in order to release the hat block. Thus, three control operations were required of each operator for each hat block, which was inefficient and time consuming on the part of the operator and also reduced the number of hat bodies which could be operated on by any given machine in a given amount of time. It is accordingly another

35 object of this invention to provide a hat block chuck which will be controlled by a single lever which also controls the operation of the machine.

40 Referring now to the drawings, for illustrative purposes the automatic chuck is shown mounted on and operatively connected to the controlling mechanism of a hat pouncing machine. It should be clearly understood however that this chuck 45 is so constructed that it may be used on and con-

ected to the control mechanism of a large number of different types of hat making machines. The pouncing machine shown is of the same general type as that shown and described in Patent No. 2,137,250.

The pouncing machine includes a base 12 (Figure 1) on the upper end of which is mounted a work supporting column 14. The automatic chuck, generally indicated at 16, is mounted on a shaft 18 (Figures 1 and 2) which is rotatably mounted on column 14 by a pair of bearings, one of which is shown at 20. Shaft 18 is driven by a motor 22 (Figure 1) through a pulley and belt assembly positioned within housing 24. When shaft 18 is driven by a motor 22, it turns a hat block, generally indicated at 26, mounted on the right-hand end of shaft 18 and held in position thereon by the jaws of chuck 16.

During operation of the machine, the crown of hat 28 mounted on block 26 is pounced by a pouncing pad, generally indicated at 30. Pouncing pad 30 is mounted on a pouncing pad assembly column, generally indicated at 32, which in turn is pivotally mounted by a stud pin 34 on a support 36 extending outwardly from and secured to base 12. This pivotal connection permits the pad 30 to move about hat 28 from the apex of the crown to the brim. Another pivotal connection (not shown) is provided to permit pad 30 to move toward and from hat 28 during each pouncing operation. The vertical pouncing movement of pad 30 is effected through mechanism driven by motor 38. As clearly described in the above-mentioned patent, suitable mechanism is provided for moving the pouncing pad into contact with the apex of hat 28 at the start of an operation, for moving the pad from the apex of the hat to its brim and out to the apex again as pouncing is effected, and then moving the pad out of contact with the hat to a rest position.

Control lever 44 is freely mounted on shaft 42 and when it is moved in a counterclockwise direction, it acts through arm 46, rod 50 and mercoid switch 48 to place motor 38 in operation, when main switch 52 is closed. Lever 44 also controls the operation of the clutch generally indicated at 54 through arm 46, rod 50 and mechanism associated with arm 56. As is described in Patent No. 2,137,250 the hydraulically powered mechanism which controls the movements of the pouncing pad about and toward and from hat 28 is placed in operation upon actuation of a control valve. In the present machine, the stem 58 (Figure 11) of this control valve is actuated by a pin on an arm 60 on the opposite end of shaft 42 from lever 44. When a main control lever 62 connected to shaft 42 is moved from the position it occupies in Figure 11 to the position it occupies in Figure 3, it turns shaft 42 (Figure 11) to move pin 64 into engagement with valve stem 58. This places in operation the hydraulic mechanism which moves the pouncing pad assembly column 32 (Figure 1) through an operating cycle. At the same time, as will be described hereinafter, lever 62 acts upon lever 44 to move it into operative position, starting pouncing pad motor 38 and actuating clutch 54 so that motor 22 drives hat block 26.

At the end of a cycle of operation suitable mechanism as described in the above patent acts upon rod 66 (Figure 1) to move it to the left. This motion is transmitted through bell crank 68 to rod 50 to move rod 50 upwardly and thus open clutch 54 and switch 48. As will be described

fully hereinafter, lever 62 also controls the operation of clutch 16, the paws of the clutch being open when lever 62 is in inoperative position (Figure 2) and gripping the hat block 26 (Figure 3) when lever 62 is in operative position.

In general the clutch consists of a frame or body, generally indicated at 70 (Figures 3 and 8), which is mounted on shaft 18. A pair of clutch jaws 72 and 74 are pivotably mounted on frame 70 and at all times are resiliently urged toward a closed position by a spring assembly generally indicated at 76. A pressure disc, generally indicated at 78, is slidably mounted on the exterior of the hub position of frame 70 for longitudinal movement with respect thereto. Pressure disc 78 has a pair of keys 80 and 82 mounted thereon which act upon arms 72a and 74a of jaws 72 and 74 to move the jaws out of engaged position with respect to hat block 26 against the action of spring assembly 76 when the pressure disc 78 is moved to the right (Figure 3) by means of a yoke, generally indicated at 84. Yoke 84 is operatively connected to lever 62 so that when lever 62 is moved into operative position (Figure 2), yoke 84 turns in a counterclockwise direction, permitting spring assembly 76 to move jaws 72 and 74 into clamping position with respect to the cylindrically-shaped center portion of hat block 26. When lever 62 is moved to an inoperative position (Figure 2), yoke 84 acts on pressure disc 78 which acts through its keys 80 and 82 to move jaws 72 and 74 to an open position.

In detail, the shaft 42 (Figures 1, 9 and 11) on which levers 44 and 62 are mounted extends transversely across the machine and is rotatably mounted thereon. An arm 60 is mounted on the right hand end of shaft 42 and has an adjustable pin mounted thereon which engages valve stem 58 when the machine is placed in operation. When valve stem 58 is pressed downwardly, it places the hydraulic system which actuates the pouncing pad assembly column 32 (Figure 1) in operation. Control lever 62 includes a hub portion 62a which is connected to shaft 42. Thus, when lever 62 is moved into and out of operative positions (Figures 1 and 3) it turns pin 64 (Figure 11) into and out of engagement with valve stem 58. Lever 44 has a hub portion 44a rotatably mounted upon shaft 42 and is held in position on shaft 42 by a collar 86 connected to shaft 42.

As is best shown in Figures 9 and 10, there is a lost motion connection between the hub portions 44a and 62a of levers 44 and 62. This lost motion connection includes a portion 62b which engages a portion 44b on hub 44a as lever 62 is moved into operative position. The lost motion connection permits lever 62 to move a greater distance than lever 44 and thus actuate yoke 84 (Figure 11) through arm 62c and mechanism associated therewith. As described hereinabove, at the end of each cycle of operation, rod 50 is moved upwardly and thus acts through arm 46 of lever 44 to move lever 44 in a clockwise direction, as viewed in Figure 3.

Arm 62c (Figures 10 and 11) on the hub portion 62a of lever 62 is pivotally connected to a link 88 by a pivot pin 90. Link 88 (Figures 1 and 11) is pivotally connected by a pivot pin 92 to an arm 94. The hub portion 94a of arm 94 is keyed to a shaft 96 rotatably mounted on a casting 100 secured to work supporting column 14 by screws 102. Shaft 96 extends transversely across the machine. Yoke 84 includes a pair of arms 84a and 84b integrally cast on a hub portion 84c which is mounted on and keyed to the right-hand end of

shaft 96, as viewed in Figure 11. Arms 84a and 84b of yoke 84 have a pair of rollers 104 and 106 mounted thereon which engage the left-hand face of pressure disc 78, as viewed in Figure 3.

All of the mechanism of the chuck mounted on shaft 18 is mounted on frame 70. Frame 70 includes a cylindrically shaped portion 70a (Figures 2, 6 and 8) which is mounted on and pinned to shaft 18 by taper pin 108. The remainder 70b of framework 70 extends radially outwardly from the outer end of portion 70a and its front face is provided with two pairs of knuckles 110 and 112 (Figure 5) aligned with the edges of radial slots 118 and 120. The chuck jaws 72 and 74 extend through slots 118 and 120 and are pivotally connected by pivot pins 114 and 116 (Figures 3 and 5) to knuckles 110 and 112. Slots 118 and 120 also extend longitudinally of the cylindrically shaped portion 70a (Figure 2) of frame 70 to form key slots 122 and 124 (Figure 2).

The jaw portions 72b and 74b of chuck jaws 72 and 74 (Figure 2) are at all times resiliently urged toward shaft 18 by means of spring assembly 76 (Figures 2 and 6). Spring assembly 76 includes a pair of spring seats, generally indicated at 126 and 128 (Figures 2 and 6). Each spring seat has a pair of knuckles 130 and 132 (Figure 6) formed thereon to which arms 72c and 74c (Figure 2) are pivotally connected by pivot pins 134 and 136.

A pair of spring supports 138 and 140 extend through holes 142 and 144 in seats 126 and 128 (Figure 6), are slidably mounted on seats 126 and 128, and have integral shoulders 138a and 140a formed thereon. Spring supports 138 and 140 have coil springs 148, 150, 152 and 154 mounted thereon which are under compression between shoulders 138a and 140a and spring seats 126 and 128. Thus, springs 148, 150, 152 and 154 at all times resiliently press against seats 126 and 128, thus tending to move spring seats 126 and 128 outwardly away from each other. Referring to Figure 2, it will thus be seen that the action of these springs tends to move the jaw portions 72b and 74b of chuck jaws 72 and 74 toward each other. Because of the particular type of spring assembly used, the chuck jaws grip independently and each will move in until it grips. Actually, there is an independent spring action on each jaw.

As pointed out hereinabove, chuck jaws 72 and 74 are moved out of gripping position by pressure disc 78 acting through keys 80 and 82. Pressure disc 78 includes a hub portion 78a which is slidably mounted on portion 70a of frame 70 for longitudinal movement with respect thereto. Keys 80 and 82 are secured to hub portion 78a by screws 156 and 158 and include actuating portions 80a and 82a which extend downwardly into slots 122 and 124. Thus, keys 80 and 82 prevent disc 78 from rotating with respect to shaft 18 and engage arms 72a and 74a of chuck jaws 72 and 74 whenever pressure disc 78 is moved to the right, as viewed in Figure 2.

The mechanism of the chuck is covered by a ring-shaped cover 160 (Figures 1 and 2), which has a plurality of bosses 162 (Figure 6) formed thereon. Screws 164 (Figure 5) extending through frame 70 threaded into holes 166 in bosses 162 and thus secure cover 160 to frame 70.

As is best shown in Figures 1, 3 and 4, the hat block, which is of the standard type, has an outer surface shaped to fit the size of the hat being worked upon. The center of the hat block is hollowed around a cylindrical-shaped portion 26a which is covered by a cushion member 168

(Figure 4), which the chuck jaws 72 and 74 grip when the hat block is mounted on the machine. A hole 170 (Figures 3 and 4) extends into the cylindrically-shaped portion 26a of hat block 26 and is adapted to receive the right-hand end of shaft 18. To prevent block 26 from turning on shaft 18, a locating pin 172 (Figures 5 and 8) is mounted on the face of frame 70. The longitudinal axis of this pin is parallel to the longitudinal axis of shaft 18 (Figure 8) and when a hat block is mounted on the machine, this pin is positioned in hole 174 (Figure 4) in block 26. Thus, pin 172 (Figures 5 and 8) prevents rotation of a hat block with respect to frame 70, and thus shaft 18. A pair of cork strips 175 and 176 are mounted upon the face of frame 70 and are so positioned as to provide a resilient seat for the hat block when it is mounted on the chuck.

To move yoke 84 from an operative position (Figure 3) to an inoperative position (Figure 2) and to dampen the recoil of the yoke when it moves from an inoperative position (Figure 2) to an operative position (Figure 3), a cam arm, generally indicated at 178 (Figure 2), is provided. Cam arm 178 is pivotally mounted on casting 100 by means of pivot pin 180. The lower end of cam arm 178 is connected to a spring 182, the other end of which is connected to a pin 184 on casting 100. Spring 182 at all times resiliently urges movement of cam arm 178 in a counterclockwise direction. Arm 94 has a roller 184 rotatably mounted on its left-hand end, as viewed in Figures 2 and 8, by means of pin 92. As the plane of movement of arm 94 is a parallel to the plane of movement of cam arm 178 (Figure 8), a roller 184 rides on the upper surface 178a of cam arm 178 as yoke 84 moves into and out of operative position.

When lever 62 is moving from the position it occupies in Figure 2 to the position it occupies in Figure 3, roller 184 moves downwardly along the surface 178a of cam arm 178, causing arm 178 to move in a clockwise direction against the tension of coil spring 182. As the springs on spring assembly 76 (Figures 2 and 6) at this time are resiliently urging the jaws of the chuck toward a closed position, arms 72a and 74a of jaws 72 and 74 act through keys 80 and 82 to move pressure disc 78 to the left as viewed in Figure 2. When roller 184 reaches the position it occupies in Figure 3, it is positioned behind a shoulder 178b (Figure 2) formed on surface 178a of cam arm 178.

When roller 184 is moving upwardly along arm 178, arm 94 acts through yoke 84, pressure disc 78, keys 80 and 82, and jaws 72 and 74 to compress the springs in spring assembly 76. To compress the springs in spring assembly 76, the combined leverage action of arms 94 and 178 is utilized. As pointed out hereinabove, when lever 94 is in the position it occupies in Figure 3, spring 182 is under tension. After roller 184 has moved past shoulder 178b, spring 182 moves arm 178 upwardly and thus arm 178 adds its leverage to that of arm 94 to compress the springs in spring assembly 76. It will be noted that the leverage of arm 178 increases as roller 184 moves upwardly thereon, and thus as the force necessary to compress the springs in spring assembly 76 increases, the combined leverage action of levers 178 and 94 likewise increases.

In operation, a hat block 26 having a hat 28 mounted thereon is mounted on the right-hand end of shaft 18. Next, control lever 62 (Figure

2) is moved in a counterclockwise direction. As it moves, it acts through link 88, arm 94, and shaft 96 (Figures 2 and 11) to move yoke 84 in a counterclockwise direction (Figure 2). As described hereinabove, chuck jaws 72 and 74 are held in an open position by yoke 84 acting through pressure disc 78, keys 80 and 82, and chuck arms 72a and 74a. The springs in spring assembly 76 (Figure 6) at all times resiliently urge jaws 72 and 74 (Figure 3) toward a closed position. Thus, when yoke 84 moves in a counterclockwise direction, the springs in spring assembly 76 act through arms 72a and 74a and keys 80 and 82 to move pressure disc 78 to the left, as viewed in Figure 2. The jaw portions 72b and 74b (Figure 2) of chuck jaws 72 and 74 move into clamping relationship with respect to the cylindrically-shaped center portion 26a of hat block 26. It will be noted that when the chuck jaws 72 and 74 (Figure 3) move into gripping position, they move both downwardly toward the axis of shaft 18 and inwardly toward disc 78, because of the positions of pins 114 and 116. The inward movement of the jaws moves the hat block 26 inwardly and clamps it against cork cushions 175 and 176 (Figure 4). This firmly connects the hat block to the chuck and prevents chattering or vibration of the hat block, which can seriously affect pouncing and other finishing operations.

After the jaws connect the hat block to chuck 16 (Figure 3), further movement of control lever 62 causes the hub portion of lever 62 to engage the portion 44a of lever 44 and move lever 44 in a counterclockwise direction. When lever 44 is moved in a counterclockwise direction, it acts through switch 48 to complete the circuit to motor 38, which drives the pouncing pad assembly 30. Lever 44 also acts through arm 46, rod 50, and mechanism connected with arm 56 to move clutch 54 into a driving position. Clutch 54 forms the driving connection between motor 22 and the belt assembly positioned within housing 24, which drives shaft 18 and thus hat block 26. After the hat is rotating and pouncing pad 30 is in operation, further movement of lever 44 in a counterclockwise direction causes pin 84 (Figure 11) to engage the valve stem 58, placing in operation the hydraulic mechanism which moves the pouncing pad assembly column 32 into engagement with hat 26 and thence through an operating cycle.

As arm 94 moves from the position it occupies in Figure 4, it acts through cam roller 184 to move cam arm 178 in a clockwise direction (Figure 3), against the tension of coil spring 182. When lever 62 is in operative position, roller 184 is positioned in engagement with a shoulder 178b on cam arm 178. Because of shoulder 178b and because the longitudinal axis of arm 94 is substantially at right angles to the radial axis of arm 180, spring 182 is prevented from acting through cam arm 178 to move lever arm 94 in a clockwise direction. Also, cam arm 178 acts through shoulder 178b (Figure 2) to hold lever 62 in operative position during an operating cycle. Thus, it will be noted that during the first portion of the movement of lever 62, toward operative position, the chuck jaws move into engagement with the cylindrically-shaped portion 26a (Figure 4) of hat block 26, and during the last portion of its movement it acts through lever 44 and shaft 42 to place the machine in operation.

At the end of an operating cycle, mechanism

acts through rod 66 (Figure 1) and bell crank 68 to move rod 50 upwardly and lever 44 with shaft 42 in a clockwise direction. This releases stem 58 (Figure 11) to close the hydraulic control valve and thus stop reciprocation of the pouncing tool about the axis of pin 84 (Figure 1). It also opens switch 48 and acts through arm 56 to move clutch 54 to an open position. Accordingly the machine comes to rest with block 26 still locked thereon. When it is desired to remove the block, lever 44 is moved in a clockwise direction, and its hub portion 44a acts through lost motion connection 44b and 62b (Figure 10) to move the hub portion 62a of lever 62 in a clockwise direction, as viewed in Figure 3. Arm 62c (Figure 10) as it moves upwardly acts through link 88 (Figure 3) to move arm 94 in a clockwise direction. As arm 94 moves upwardly, roller 184 moves out of seat 178b (Figure 8) toward pivot pin 180. This permits spring 182 to move arm 178 in a counterclockwise direction, which, as it turns, moves arm 94 upwardly. As arm 94 moves upwardly, it turns shaft 96 and yoke 84 in a clockwise direction. Yoke 84 acts upon pressure discs 78 to move it from the position it occupies in Figure 3 to the position it occupies in Figure 2. As disc 78 moves outwardly with respect to shaft 18, keys 80 and 82 engage arms 72a and 74a of chuck jaws 72 and 74 and moves the jaws outwardly with respect to shaft 18. When the jaws move outwardly, they release their grip upon the cylindrically-shaped portion 26a of hat block 26, so that the hat block may be moved from the machine.

Thus, a practical and efficient automatic chuck for a hat finishing machine has been disclosed, the operation of which is controlled by one lever which also controls the operation of the hat finishing machine. Furthermore, it will be seen that the automatic chuck is so constructed and the control lever so connected thereto that the automatic chuck is placed in operative condition before the hat finishing machine starts its operation and remains in operative position throughout the operating cycle of the machine. It will thus be seen that the several objects hereinabove mentioned, as well as many others, have been successfully accomplished.

As many possible embodiments may be made of the above invention, and as many changes might be made in the embodiment above set forth, it is to be understood that all matter hereinabove set forth or shown in the accompanying drawings is to be interpreted as illustrative and not in a limiting sense.

What is claimed is:

1. In an automatic chuck for a hat finishing machine, in combination, a chuck for mounting hat blocks on said machine, a control lever starting and stopping the operation of said machine as said lever is moved into and out of operative position, said chuck including a pair of jaws movable into and out of operative position, means for moving said jaws out operative position, and means for moving said jaws into operative position, and means operatively connecting said control lever to said two last-mentioned means, said control lever controlling the operation of said hat finishing machine and said chuck.
2. In a hat finishing machine including a rotatable support for a hat block chuck, in combination, a chuck mounted on said support, said chuck including a pair of pivotally mounted jaws movable into clamping relationship with respect to a portion of a hat block, spring means acting

upon said jaws for moving said jaws into closed position, a member movable longitudinally of said support acting upon said jaws for moving said jaws out of operative position, a control lever starting and stopping the operation of said machine as said lever is moved into and out of operative position, means for moving said member longitudinally of said support to open said chuck jaws, and means operatively connecting said lever and said last-mentioned means, movement of said member in one direction opening said chuck jaws and in the other direction controlling the closing of said jaws, whereby upon movement of said control lever to operative position said chuck jaws close and said machine starts and on movement of said control lever in the opposite direction said machine is stopped.

3. In an automatic chuck for a hat finishing machine, in combination, a shaft mounted on said hat finishing machine, means for rotatably driving said shaft, a chuck mounted on said shaft, said chuck including a pair of jaws movable into and out of operative position with respect to a portion of a hat block, spring means for moving said chuck jaws into operative position, a disc mounted on said shaft, said disc including a hub portion engaging portions of said jaws, means for moving said disc in one direction to open said chuck jaws, means controlling the movement of said disc in the opposite direction, and means controlling said last-mentioned means including a control lever, a yoke member, spring means for moving said member into engagement with said disc, and means operatively connecting said control lever to said yoke member.

4. In an automatic chuck for a hat finishing machine, in combination, a shaft on said machine, means for rotating said shaft, means for mounting a hat block on one end of said shaft, a chuck including a face plate and a pair of co-operating gripping elements, the base of said hat block engaging said face plate when said hat block is mounted on said shaft, means mounting said gripping elements on said chuck so that the gripping portions of said gripping elements move inwardly toward the axis of said shaft and rearwardly toward the face of said face plate, whereby said gripping elements draw said hat block against said face plate, and control means for moving said gripping elements into and out of gripping position.

5. In an automatic chuck for a hat finishing machine, in combination, a shaft mounted on said hat finishing machine, means for rotatably driving said shaft, a chuck mounted on said shaft, said chuck including a pair of jaws movable into and out of operative position with respect to a portion of a hat block, spring means for moving said chuck jaws into operative position, a disc mounted on said shaft, said disc including a hub portion engaging portions of said jaws, means for moving said disc in one direction to open said chuck jaws, said spring means acting through said jaws and the hub portion of said disc to move said disc into the opposite direction to close said jaws, a control lever for starting and stopping said machine as it is moved into and out of operative position, means connected to said lever and acting upon said disc as said lever is moved to move said disc against the action of said spring means to open said jaws and to control movement of said disc in the opposite direction as said jaws are closed by said spring means.

6. In an automatic chuck for a hat finishing machine, in combination, a shaft on said ma-

chine, means for rotating said shaft, means for mounting a hat block on one end of said shaft, a chuck including a face plate and a pair of co-operating gripping elements, the base of said hat block engaging said face plate when said hat block is mounted on said shaft, means mounting said gripping elements on said chuck so that the gripping portions of said gripping elements move inwardly toward the axis of said shaft and rearwardly toward the face of said face plate, whereby said gripping elements draw said hat block against said face plate, a control lever for starting and stopping said machine as said control lever is moved into and out of operative position, spring means acting upon said gripping elements for moving them into closed position, means for moving said gripping elements into open position and means connecting said lever to said last mentioned means, said control lever acting through said last mentioned means to control the position of said gripping elements.

7. In apparatus of the character described, in combination, a frame, a shaft rotatably mounted in said frame, means to lock a hat block on said shaft, means for supporting a hat processing tool adjacent a hat mounted on said block, means for driving said shaft, a movable controlling arm, mechanism between said first-mentioned means and said controlling arm whose actuation locks a hat block on said shaft when said controlling arm is moved to a first position, and mechanism interposed between said controlling arm and said driving means to actuate said driving means upon movement of said controlling arm beyond said first position whereby a hat block must be securely locked on said shaft before the machine is placed in operation.

8. In apparatus of the character described, in combination, a frame, a shaft rotatably mounted in said frame, means to lock a hat block on said shaft, means for supporting a hat processing tool adjacent a hat mounted on said block, means for driving said shaft and moving said tool through a cycle of operation, a movable controlling arm, mechanism between said first-mentioned means and said controlling arm whose actuation locks a hat block on said shaft when said controlling arm is moved to a first position, mechanism interposed between said controlling arm and said driving means to actuate said driving means upon movement of said controlling arm beyond said first position, and mechanism responsive to completion of said cycle of operation for stopping said driving means.

9. In apparatus of the character described, in combination, a frame, a shaft rotatably mounted in said frame, means including jaws pressed inwardly by springs to lock a hat block on said shaft, slideable means capable upon actuation of separating said jaws against the action of such springs, means for supporting a hat processing tool adjacent a hat mounted on said block, means for driving said shaft, a movable controlling arm, mechanism between said slideable means and said controlling arm to release said jaws to thereby lock a hat block on said shaft when said controlling arm is moved to a first position, and mechanism interposed between said controlling arm and said driving means to actuate said driving means upon movement of said controlling arm beyond said first position.

10. In apparatus of the character described, in combination, a frame, a shaft rotatably mounted in said frame, means including jaws pressed inwardly by springs to lock a hat block on said

shaft, slideable means capable upon actuation of separating said jaws against the action of such springs, means for supporting a hat processing tool adjacent a hat mounted on said block, means for driving said shaft and moving said tool through a cycle of operation, a movable controlling arm, mechanism between said slideable means and said controlling arm to release said jaws to thereby lock a hat block on said shaft when said controlling arm is moved to a first position, mechanism interposed between said controlling arm and said driving means to actuate said driving means upon movement of said controlling arm beyond said first position, and mechanism responsive to completion of said cycle of operation for stopping said last-mentioned means.

11. In apparatus of the character described, in combination, a frame, a shaft rotatably mounted in said frame, means including jaws pressed inwardly by springs to lock a hat block on said shaft, slideable means capable upon actuation of separating said jaws against the action of such springs, means for supporting a hat processing tool adjacent a hat mounted on said block, means for driving said shaft, a movable controlling arm, a leverage system between said slideable means and said controlling arm to release said jaws and to thereby lock a hat block on said shaft when said controlling arm is moved to a first position, and mechanism interposed between said controlling arm and said driving means to actuate said driving means upon movement of said controlling arm beyond said first position.

12. In apparatus of the character described, in combination, a frame, a shaft rotatably mounted in said frame, means including jaws pressed inwardly by springs to lock a hat block on said shaft, a slideable part capable upon actuation of separating said jaws against the action of said springs, means for driving said shaft, a lever pivotally mounted on said frame, a bell crank pivoted to move said slideable part with or against the action of said springs, means forming a linkage system between said crank and said lever arm to release said jaws and lock said block on said shaft when said lever is moved to a first position, and mechanism interposed between said lever arm and said driving means to actuate said driving means upon movement of said controlling arm beyond said first position.

13. In apparatus of the character described, in combination, a frame, a shaft rotatably mounted in said frame, means including jaws pressed inwardly by springs to lock a hat block on said shaft, a slideable part capable upon actuation of separating said jaws against the action of such springs, means for driving said shaft, a lever pivotally mounted on said frame, a bell crank horizontally pivoted with one arm engaging said slideable part, a spring connected to the other arm of said bell crank and anchored to exert tension thereon against said first-mentioned springs through said slideable part, means forming a linkage system between said last-mentioned end of said bell crank and said lever to release said jaws and to thereby lock a hat block on said shaft when said lever is moved to a first position, and mechanism interposed between said controlling arm and said driving means to actuate said driving means upon movement of said controlling arm beyond said first position.

14. In apparatus of the character described, in combination, a frame, a shaft rotatably mounted in said frame, means to lock a hat block on said shaft, means for supporting a hat processing tool

adjacent a hat mounted on said block, means for driving said shaft, a movable controlling arm, mechanism including a lost motion connection between said controlling arm and said driving means to effect a locking action between a hat block and said shaft when said controlling arm is moved to a first position and to actuate said driving means upon movement of said controlling arm beyond said first position.

15. In apparatus of the character described, in combination, a frame, a shaft rotatably mounted in said frame, means to lock a hat block on said shaft, means for supporting a hat processing tool adjacent a hat mounted on said block, means for driving said shaft and moving said tool through a cycle of operation, a movable controlling arm, mechanism including a lost motion connection between said controlling arm and said driving means to effect a locking action between a hat block and said shaft when said controlling arm is moved to a first position and to actuate said driving means upon movement of said controlling arm beyond said first position, and mechanism responsive to completion of said cycle of operation for stopping said driving means, said lost motion connection preventing the unlocking of said hat block during such stopping action.

16. In apparatus of the character described, in combination, a frame, a shaft rotatably mounted in said frame, means including jaws pressed inwardly by springs to lock a hat block on said shaft, a slideable part capable upon actuation of separating said jaws against the action of said springs, means for driving said shaft, a lever pivotally mounted on said frame, a bell crank pivoted to move said slideable part with or against the action of said springs, means forming a linkage system between said crank and said lever arm to release said jaws and lock said block on said shaft when said lever is moved to a first position, and mechanism including a lost motion connection between said lever arm and said driving means to actuate said driving means upon movement of said controlling arm beyond said first position.

17. In apparatus of the character described, in combination, a frame, a shaft rotatably mounted in said frame, means including jaws pressed inwardly by springs to lock a hat block on said shaft, a slideable part capable upon actuation of separating said jaws against the action of said springs, means for driving said shaft and moving said tool through a cycle of operation, a lever pivotally mounted on said frame, a bell crank pivoted to move said slideable part with or against the action of said springs, means forming a linkage system between said crank and said lever arm to release said jaws and lock said block on said shaft when said lever is moved to a first position, mechanism including a lost motion connection between said lever arm and said driving means to actuate said driving means upon movement of said controlling arm beyond said first position, and mechanism responsive to completion of said cycle of operation for stopping said driving means, the said lost motion connection preventing the unlocking of said hat block during such stopping action.

FREDERICK R. MARINDIN.
